UNITED STATES PATENT OFFICE.

CHARLES C. DODGE, OF WOLLASTON, MASSACHUSETTS, ASSIGNOR TO THE DODGE LUBRICATOR COMPANY, OF BOSTON, MASSACHUSETTS, A CORPORATION OF MASSACHUSETTS.

SPARK-TIMING APPARATUS.

No. 882,876.

Specification of Letters Patent. Patented March 24, 1908.

Application filed November 29, 1905. Serial No. 289,617.

To all whom it may concern:

Be it known that I, CHARLES C. DODGE, of Wollaston, in the county of Norfolk and State of Massachusetts, have invented certain new and useful Improvements in Spark-Timing Apparatus, of which the following is a specification.

This invention has relation to spark timing apparatus for employment in connection with the spark plug circuits of internal combustion engines, and has for its object to provide certain improvements therein which are illustrated upon the accompanying drawings and described in the following specification and pointed out with particularity in the appended claims.

Referring to the accompanying drawings—Figure 1 represents in plan view and with the cover removed a device embodying the invention. Fig. 2 represents a vertical transverse section through the same and illustrates the cover in its proper position.

The device comprises a support formed as a casing *a* which is internally threaded for the reception of a cover *b* which may be screwed therein. The casing is formed of a suitable insulating material such as fiber, wood pulp, or any other substance which is a good nonconductor of electricity. Through an aperture in the bottom of the casing extends a bushing *c* which is preferably of metal which constitutes a journal for a rotatable arbor *d*. This arbor is formed with an enlarged socket at the end for the reception of a shaft *e* by which rotary movement may be imparted to the arbor. The arbor and the shaft are secured together by any suitable means, such as a screw *e'*. To the arbor is attached a movable contact which is adapted to be engaged successively with one or more stationary contacts for the purpose of closing the circuit through one or more spark plugs. The stationary contacts may conveniently take the form of bolts *f* having circular flat heads *f'*, said bolts being passed outwardly through the bottom wall of the casing, and the heads being embedded in the casing so that the upper surfaces of the heads are flush with the upper surfaces of said bottom wall, as clearly shown in Fig. 2. The bolts are securely held in place by washers *f*² and nuts *f*³. Nuts *f*⁴ are utilized for securing to the bolts the ends of conductors *g*, which form portions of the spark plug cir-

cuits. Thus the bolts consist of combined 55 stationary contacts and binding screws. Any suitable number of these stationary contacts may be utilized, their number being dependent upon the number of spark plugs through which it is desired to pass a current 60 of electricity for the purpose of forming a spark. The contacts are arranged at the same radial distance from the axis of the arbor *d* and are symmetrically placed within the casing. 65

The movable contact consists of a roll *h* which is journaled on an arm radiating from the arbor. Said arm comprises a bolt *h'* and a yoke *i* into which it is passed and which is secured in place by a nut *h*². The yoke is in 70 turn pivoted upon a pin *j* which is passed transversely through the end of the arbor *d* which extends into the casing. The rotation of the arbor *d* affects a circular or revoluble movement of the roller *h* so that it is 75 caused to engage successively the contacts *f'*. To insure a proper engagement of the contacts *h* and *f'*, a spring *k* is passed through the arbor *d* and through the pin *j* and its free end rests upon the free end of the yoke. 80 The spring thus serves to hold the roller or movable contact *h* yielding against the bottom wall of the casing or support and against the contacts *f'* and also to secure the pin *j* against movement. 85

In order that the operator may change the time at which the spark occurs with reference to the balance of the cycle of operations of the engine, the casing *a* is provided with an arm *a'* radiating therefrom and having 90 connected to it a link *a*² leading to the suitable lever (not shown) which is adapted to be moved by the operator for the purpose of rotatably shifting the casing. The shaft *e* is operated by any suitable mechanism for 95 an element which is actuated by an engine.

The roll *h* is of such width that as it engages the flat stationary contacts *f'*, portions of the periphery of the roll have a sliding contact with the exposed faces of said contacts, 100 due to the fact that the roll *h* is traveling in a circular path. Thus I not only secure a sufficiently positive sliding engagement of the contacts to insure a closing of the circuit through the spark plug, but at the same time 105 I eliminate much of the friction and therefore reduce the wear of the parts.

It will be understood that the spark plug

circuits include in addition to the stationary contacts, the shaft *e*, arbor *d*, the yoke *i* and the roll *h*.

Having thus explained the nature of the 5 invention and described a way of constructing and using the same, although without attempting to point out all the forms in which it may be made or all the modes of its use, what I claim is—

- 10 1. A spark timing device comprising a casing having a flat surface, one or more contacts whose surfaces are flush with the flat surface of the casing, an arbor perpendicular to said flat surface, an arm carried by said arbor extending laterally therefrom, and a rotatable cylindrical contact on the end of said arbor adapted to roll over said stationary contact or contacts in its rotation.
- 15 2. A spark timing device comprising a casing formed of insulating material and having a flat surface, one or more contacts on said casing having their faces flush with the flat surface of the casing, an arbor perpendicular to said surface, an arm on said arbor, and a movable contact comprising a cylindrical roll journaled on the end of said arm on an axis longitudinal of said arm and adapted to roll over said stationary contact or contacts, substantially as described.
- 20 25 3. A spark timing device comprising a casing formed of insulating material, stationary contacts secured to said casing and having their faces located in the same plane,

an arbor perpendicular to said plane, an arm pivoted on said arbor and extending laterally therefrom, a movable contact consisting of a roll journaled on said arm on an axis longitudinal of said arm, and a spring for holding said roll towards the face of said casing, substantially as described. 35

4. A spark timing device comprising a casing formed of insulating material, flat stationary contacts having their faces in the same plane, an arbor, an arm pivoted to said arbor, a roll journaled on the end of said arm, and a spring bearing against the free end of said arm, substantially as described. 40

5. A spark timing device comprising a casing formed of insulating material and having a flat surface, a cover for closing said casing, an arbor extending into said casing, a yoke in said casing pivoted upon the end of the arbor, a movable contact consisting of a roll journaled upon the free end of said arm, stationary contacts consisting of flat headed bolts passed through said casing and having their heads substantially flush with said flat surface, and means on the ends of said bolts for securing electrical conductors thereto. 50

55 In testimony whereof I have affixed my signature, in presence of two witnesses.

CHARLES C. DODGE.
